UNITED STATES PATENT OFFICE.

FRANCIS J. FEE, OF NEW YORK, N. Y.

DESIGN FOR A SPRINKLER-HEAD LINK ELEMENT.

51,807.

Specification for Design.

Patented Feb. 26, 1918.

Application filed August 17, 1917. Serial No. 186,809. Term of patent 14 years.

To all whom it may concern:

Be it known that I, FRANCIS J. FEE, a citizen of the United States, residing in the city of New York, borough of the Bronx, in the county of Bronx and State of New York, have invented a new, original, and ornamental Design for a Sprinkler-Head Link Element, of which the following is a specification, reference being had to the accompanying drawings, forming part thereof.

Figure 1 is a perspective view showing particularly the inner face of the element; and

Fig. 2 is a rear elevation of the same showing my new design.

I claim:

The ornamental design for a sprinkler head link element, as shown.

FRANCIS J. FEE.
